UNITED STATES PATENT OFFICE.

MARSHALL H. WARD, OF BROOKLYN, NEW YORK, AND EDWARD L. AURAND, OF TEANECK, NEW JERSEY, ASSIGNEES TO AMERICAN RADIATOR COMPANY, OF NEW YORK, N. Y., A CORPORATION OF NEW JERSEY.

COOLING SYSTEM FOR INTERNAL-COMBUSTION ENGINES.

Application filed March 22, 1924. Serial No. 701,162.

Our invention relates to new and useful improvements in cooling systems for internal combustion engines, and more particularly to those employing a liquid cooling medium in contact with the part or parts to be cooled, and in which the temperature of the liquid cooling medium is controlled by regulation of the vapor pressure of the cooling liquid.

10 In cooling systems of this type, it has heretofore been proposed to regulate the vapor pressure either by thermostatically controlled means responsive to temperature variations in the cooling liquid, or by valves actuated by the pressure difference existing between the closed cooling system and the surrounding air. In one of these types, the vapor pressure of the cooling liquid is regulated at a point below the normal barometric pressure by use of either of the controlling means heretofore mentioned.

The present invention contemplates the provision of improved and simplified means for controlling the vapor pressure, and is particularly, although not necessarily, adaptable to systems of the type mentioned, wherein the intake manifold of the engine is employed as the source of sub-atmospheric pressure.

20 One of the important objects of the invention, among others which will appear, is to provide efficient means for maintaining the pressure in the cooling system substantially constant without disturbing, or irrespective of, the pressure conditions in the engine manifold existing during the normal operation of the engine.

Other objects will appear from the detailed description of the invention herein-after given.

The invention consists in the improvements to be more fully described hereinafter, and the novelty of which will be particularly pointed out and distinctly claimed.

25 We have fully and clearly illustrated a preferred embodiment of our invention in the accompanying drawings, to be taken as a part of this specification, and wherein—

Figure 1 is a view in side elevation, partly in section, of one type of internal combustion engine with our invention applied thereto;

Fig. 2 is a section on the line 2—2 of Fig. 1, and showing certain parts in dotted lines;

Fig. 3 is a vertical, longitudinal section

through a pump and overflow device employed in our invention;

Fig. 4 is a vertical, longitudinal section through a valve forming one of the elements of our invention;

Fig. 5 is a section on the line 5—5 of Fig. 1;

Fig. 6 is a view in side elevation, partly in section, of another form of the same invention, and

Fig. 7 is a vertical, longitudinal section through another embodiment of a pump and overflow device.

Referring to the drawings by characters of reference, 1 designates, generally, a multiple cylinder, internal combustion engine, which, by way of example, may be of any of the well-known liquid-cooled types such as are commonly employed as the source of power for driving motor vehicles; although it will be understood that this illustration is merely by way of example, as the invention is applicable to liquid-cooled internal combustion engines generally, irrespective of the use to which the same may be put. The engine shown includes the usual crank-case 2, piston cylinders 3, the latter being arranged within a chamber formed by the usual jackets 4 and a head 5, forming a chamber or space

for a suitable liquid cooling medium, for example, water, or a mixture of water and alcohol, surrounding the cylinders and adapted to cool the same. The engine is provided with a suitable intake manifold 6 in which suction is created in the usual manner to draw an explosive mixture from a carburetor (not shown) into the cylinders to be therein ignited to drive the engine pistons.

The head 5 is provided with an outlet connection 7, to which is connected one end of an outlet pipe or conduit 8, the opposite end of which is connected to and discharges into the upper portion of a radiator 9 acting as a cooling element or condenser, as will be hereinafter more fully set forth.

The radiator preferably comprises a suitable air-cooled core 10, above which is a receiving chamber 11 into which the outlet pipe 8 discharges, and below which is a tank 12 to receive water of condensation. The radiator is provided preferably at one side of the core 10 with a sealed column or passage 13 closed at its upper end by a partition 14, and communicating at its lower end (see

70

75

80

85

90

95

100

105

Fig. 2) with the upper portion of the tank 12, for a purpose to be presently described. Connected to the lower portion of the radiator below the liquid level therein, is a return flow connection 15 leading to the inlet side 16 of a suitable pump 17, which may be of the rotary geared piston type driven by any suitable transmission connection from the engine crank shaft. The outlet 18 of the pump is connected to an overflow device comprising a column 19 having an outlet emptying into the liquid cooling space of the engine jacket. This overflow device may take a number of forms, but preferably consists of a vertical column in which is arranged a vertical partition wall 20 dividing the column into an up-flow passage 21 and a down-flow passage 22, which communicate at their upper ends through a duct 23 between the upper end of wall 20 and the top wall of the casing. The liquid from the pump 17 passes through the passages 21 and 22 and out through a port 24 at the base of passage 22 to the liquid-containing space of the engine jacket. The partition 20 is of such height that its upper end approximates the liquid level desired to be maintained in the engine jacket.

In the top of the column 19 is a port 24^a connected by a pipe or other suitable conduit 19^a to the steam space of the head 5, which permits steam pressure to exist over the top of the passages 21, 22, so as to insure balance of pressures between the overflow and the space above the water in the cylinder head, in order that the cooling medium may flow by gravity from the overflow to the water jackets.

In the arrangement as so far described, the liquid level in the jacket is maintained at such a point as to provide a steam-disengaging space above the liquid, the level being determined, for example, by the height of the wall 20 heretofore described. When the engine is running, vapor is disengaged from the liquid in the cooling space in the jacket, flows out of the head 5 through the connection 7 and pipe 8 and is discharged into the receiving chamber 11 at the upper portion of the radiator or condenser, and passing down through the core 10, is condensed therein, the liquid of condensation being collected in the tank 12 at the base of the condenser. From the tank 12 the liquid is drawn by the pump 17 and is discharged into the device 19, whence it passes to the engine jacket through port 24 to maintain the supply of cooling liquid therein.

The radiator or condenser core may be, and preferably is, cooled by a suction fan 10^a mounted on the shaft 10^b of said pump 17, said shaft carrying a belt pulley 10^c adapted to be driven by an endless belt 10^d from a pulley 10^e on a magneto shaft or other part driven from the engine shaft.

Our present invention contemplates the operation of the system while maintaining a sub-atmospheric pressure in the cooling system, in order to maintain a constant temperature of the cooling liquid in the engine cooling space, and for this purpose we connect the radiator or condenser with the inlet manifold of the engine, and employ the sub-atmospheric pressure conditions therein to create the desired sub-atmospheric pressure in the cooling system. In the embodiment herein shown, the object just stated is achieved by connecting to the upper portion of the passage 13 one end of a suitable conduit 25, the opposite end of which is arranged within the intake manifold, so that the suction in the latter operates through said connection to draw air from the condenser and create a sub-atmospheric pressure therein.

We will now proceed to describe improved means for automatically regulating and controlling the pressure in the cooling system without disturbing the normal operating conditions in the intake manifold. This means, in its preferred embodiment, comprises a valve device 26 constructed to maintain a desired or determined sub-atmospheric pressure in the cooling system for all degrees of pressure, or variations of pressure, in the manifold—that is, the conditions attending the operation of the engine, and also to maintain the air flow from the cooling system to the manifold substantially constant at the minimum rate.

This valve consists of a casing or body 27 having concentric cylindrical chambers 28, 29, the former connecting through a port 30 with a portion of the pipe 25 leading to the engine manifold, and the chamber 29 connecting through a port 31 with that portion of the pipe 25 leading to the condenser. The cylinders 28, 29 are preferably arranged axially concentric and are provided with internal sleeves 32, 33, respectively. The cylinder 28 is provided in its side wall with a longitudinal passage or port 34 coextensive in length with the cylinder 28, and connecting with the interior of the sleeve 32 through a narrow slot 35 extending longitudinally through the wall of the sleeve, and the cylinder 29 is correspondingly formed with a longitudinal passage 36 which communicates through an elongated narrow slot 37 in the sleeve 33 with the interior of the cylinder 29. Within the sleeves 32, 33 is arranged a plunger valve, consisting of a piston valve member 38 extending into the upper sleeve 32, and a larger piston valve head 39 slidably arranged within the lower sleeve 33, said pistons being rigidly connected so as to move in unison. The plunger valve embodying the two piston heads is slidable longitudinally in the sleeves, and during the sliding movement controls the area of the

openings through the slots 35, 37, respectively, which establish communication between the passages 34, 35, and the chambers 28, 29, respectively. The areas of the slots 5 35, 37 and the piston chambers and pistons 38, 39, are so proportioned as to maintain the proper sub-atmospheric pressure conditions desired in both the manifold and the radiator or condenser. If the vacuum condition 10 or sub-atmospheric pressure which is maintained in the manifold during the normal operation of the engine be approximately 20 inches of mercury, and it should be desired to maintain a greater pressure in 15 the condenser—say, approximately $\frac{1}{2}$ inch of mercury—the operation of a properly proportioned structure for this purpose will be as follows:

The vacuum or sub-atmospheric pressure 20 condition in the manifold causes the plungers to rise in the cylinders 28, 29, thereby closing the port or slot 35, except for a slight orifice at the upper end of the latter, under which conditions there will be a 25 vacuum of approximately 20 inches of mercury in the chamber 28, and a vacuum of approximately 4 inches of mercury in the passage 34, due to the restricted portion of the port exposed above the piston 38, which 30 pressure will also exist in that portion of the lower chamber 29 above the piston 39. At the same time that the piston covers the passage 35, as heretofore described, the 35 larger piston head 39 in the lower chamber 35 moves lengthwise of the port or slot 37, so that only a small area of said slot affords communication between the upper part of the lower cylinder and the port or passage 36, whereby the sub-atmospheric pressure in 40 the passage 36, and that portion of the lower cylinder beneath the piston 39 is reduced to approximately $\frac{1}{2}$ inch of mercury, or that pressure desired to be maintained in the 45 cooling system. The lower portion of the chamber 29 being in direct communication with the radiator or condenser, the vacuum in the latter will be the same as that in the lower portion of the chamber 29.

In the embodiment above described, the 50 only condition creating a sub-atmospheric pressure in the condenser is the suction existing by reason of the higher vacuum in the manifold, but due to the condensation of steam in the condenser a further and 55 higher vacuum in the condenser might result—say, as high as 4 inches of mercury—which, under some conditions, may be higher than that necessary to obtain the desired cooling conditions. In order to prevent the 60 condensation creating an excess vacuum, the controlling valve described embodies means for admitting air to the condenser in order to reduce the vacuum to the desired point. For this purpose the valve body or casing 65 is provided with an extension 40 having a

chamber 41, preferably axially concentric with the chambers 28, 29, heretofore described, the wall of the extension being provided with one or more ports 42 open to the atmosphere. The plunger valve heretofore 70 described carries a valve member which operates with the port or ports 42 to admit air to the lower chamber 41, and consequently to the radiator or condenser whenever the vacuum in the latter rises above a 75 desired point. This valve consists preferably of a piston disk 43 on the lower end of a stem 44 which is integral with the lower end portion of the piston 39, said stem being provided with a circumferential reduced 80 neck constituting a passage 45. The operation of the construction just described is as follows:

When the sub-atmospheric pressure in the condenser, and consequently in the lower chamber 29, increases above that desired, the resistance to the upward movement of the valve plungers under the influence of the vacuum in the manifold, will be increased, so that the plunger valve takes such position that the neck or groove 45 spans or registers more or less with the ports 42, which will result in air flowing through said ports into the space 45, the lower chamber 29 and through conduit 25 to the condenser, thereby reducing the sub-atmospheric pressure to the desired point. As soon as the sub-atmospheric pressure is reduced by the introduction of air as just described, the plungers assume the normal position with the piston valve 43 above the ports 42, and cutting off communication between the same, the lower chamber and the condenser, under which conditions the desired pressure is maintained in both the manifold and the condenser. It will be understood that the system is sealed against ingress of air other than that admitted by the controlling valve described.

The valve also has another important function, namely, to relieve excess pressure which may occur in the system, due to failure of the system to function properly as a whole. This takes place in the following manner: Any pressure within the cooling system greater than the negative pressure at which the valve is designed to operate will force steam or vapor through the conduit 25 into the lower chamber 29, and acting on the lower surface of the piston 39 causes the valve to rise in the cylinders sufficiently far to raise the disk 43 completely out of the chamber 41 and permit such steam or vapor to escape freely into the outer air through the holes 42. When such excess pressure has been dissipated, the valve will return to its normal operating position and resume its function as heretofore described.

The pipe 19^a is connected to one end of a pipe 46 constituting a steam by-pass, the other end of which enters the water chamber 130

in the base of the radiator or condenser, and is reversed and inserted, as at 47, for a suitable distance into the inlet end of the pipe 15. The external diameter of the part 47 is less than the internal diameter of the inlet end of pipe 15, so that water is free to flow into the latter pipe, but steam is also admitted into the latter, thereby serving to raise the temperature of the water to a point approximating that of the steam, in order that the water fed by the pump to the jackets will be approximately the temperature of the water contained within the jackets.

It will be understood that the water fed to passage 21 by the pump does not completely fill the column 21, but merely rises to a point where it spills over the upper edge of the wall 20.

It will be understood that the system may be provided initially with a suitable supply of cooling liquid through one or more supply inlets; for example, there may be a filler inlet 11^a on the radiator top, closed by a suitable cap 11^b, and an inlet 5^a having a removable cap 5^b may also open into the cooling jacket 5, as shown in dotted lines in Figs. 1, 2 and 6.

In Figs. 6 and 7 we have shown another embodiment in which all of the elements heretofore described are the same, except the specific structure of the overflow device. In this construction the pump 17 discharges into a column 19^b having an up-flow passage 21^a separated from a down-flow passage 22^a by a partition 20^a, the lower end of the passage 22^a discharging through a port 24^a into the engine jacket in the same manner as the overflow part heretofore described. In this embodiment the column is also provided with a third passage 48 communicating through a port 49 with the space above the passages 21^a, 22^a, and at its lower end provided with an outlet 50 connected by a pipe 51 with the water-receiving space or tank at the lower portion of the condenser. By this means any excess water existing in the overflow column is by-passed back to the radiator, and the desired level of water in the jackets maintained. It will be understood that in the preferred form only the proper amount of water to maintain the desired level in the jackets is used, but by the modified form an excess of water may be carried, if desired, and at the same time the proper level of water be maintained in the jackets.

The controlling means heretofore described is designed to, and does, take care of all variations which may exist between the pressure in the cooling system and the pressure in the engine manifold during the running of the engine, without disturbing the normal conditions existing in the manifold.

First. When the sub-atmospheric pressure in the manifold exceeds that in the cooling system, the valve functions so as to restrict

the connection between the condenser and the manifold to an extent which will provide that just sufficient air be withdrawn from the condenser to maintain the desired pressure therein, without permitting an excessive quantity of air to be taken into the manifold.

Second. When the sub-atmospheric pressure in the condenser and cooling system exceeds that desired, the valve functions to admit sufficient air to the condenser and cooling system to reduce the sub-atmospheric pressure, and to maintain the desired sub-atmospheric pressure in the cooling system, but without admitting air to the engine manifold.

Third. When for any reason the steam or vapor pressure in the cooling system exceeds a desired maximum, the valve functions to relieve the pressure to the atmosphere without effecting the pressure conditions in the manifold.

Fourth. When the sub-atmospheric pressure condition in the manifold and the cooling system are equal, or substantially balanced, and provided that the sub-atmospheric pressure in the condenser is greater than that desired, the valve will operate to reduce the vacuum in the condenser without admitting air to the manifold.

Herein wherever we speak of an increase of sub-atmospheric pressure, is meant an increase of the differential between the atmospheric pressure and the lower pressure in the cooling system or the suction connection.

What we claim and desire to secure by Letters Patent of the United States is:

1. A cooling system of the character described comprising a combustion engine having a cooling space and a fuel-suction inlet, a condenser, a passage connecting the cooling space with the condenser and discharging into the latter, a return passage from the condenser to the cooling space, a suction connection between the condenser and said fuel suction inlet, and pressure controlled means responsive to pressure in said suction connection to regulate the suction exerted by the said suction connection to thereby maintain a determined pressure in the cooling system regardless of variations of pressure in said fuel suction inlet.

2. A cooling system of the character described comprising an internal combustion engine having a cooling space and a fuel suction inlet, a condenser, a vapor discharge from the cooling space into the condenser, a liquid return from the condenser to said cooling space, a suction pipe connecting the condenser with said fuel suction inlet, and a balanced valve in said suction pipe and responsive to variations in pressure for maintaining a desired pressure in the cooling system without disturbing normal pressure conditions in said fuel passage.

3. A cooling system of the character de-

scribed comprising an internal combustion engine having a cooling space and a fuel suction inlet, a condenser, a vapor discharge from the cooling space into the condenser, a liquid return from the condenser to said cooling space, a suction pipe connecting the condenser with said fuel suction inlet, and a valve in said suction pipe and responsive to variations in pressure for maintaining a desired pressure in the cooling system and including a piston valve member having ports connecting the condenser side of the piston valve with the engine suction side.

4. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, and means in said suction connection responsive to pressure in the suction inlet to regulate the pressure in the condenser.

5. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, and means in said suction connection responsive to pressure in the suction inlet to regulate the suction exerted on the condenser to permit a relatively greater pressure in the condenser.

6. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, a valve casing in said suction connection and having a port leading to the suction inlet and the condenser, and a valve controlling said port and responsive to suction inlet pressure to permit a relatively greater pressure in the condenser.

7. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, a valve casing in said suction connection and including chambers of differing diameters, connected piston valves in said chambers, a chamber of smaller diameter being connected to the suction side and

a chamber of larger diameter being connected to the condenser side, and slotted ports connecting said chambers and the latter with the suction side and the condenser side respectively, said ports being controlled by 70 said piston valves.

8. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, a valve casing in 80 said suction connection and including chambers of differing diameters, connected piston valves in said chambers, a chamber of smaller diameter being connected to the suction side and a chamber of larger diameter being connected to the condenser side, slotted ports connecting said chambers and the latter with the suction side and the condenser side respectively, said ports being controlled by said piston valves, and means controlled 90 by said valves for admitting air to the condenser side of said suction connection.

9. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet, a valve casing in 95 said suction connection and including chambers of differing diameters, connected piston valves in said chambers, a chamber of smaller diameter being connected to the suction side and a chamber of larger diameter being connected to the condenser side, slotted ports connecting said chambers and the latter with the suction side and the condenser side respectively, said ports being controlled by 100 said piston valves, an air port on the condenser side of the valve casing, and means operated by said valves for controlling said port.

10. A cooling system of the character described comprising a combustion engine having a cooling space and a fuel suction inlet, a condenser, a passage connecting the cooling space with the condenser and discharging into the latter, a return passage from the condenser to the cooling space, a suction connection between the condenser and the fuel suction inlet whereby a sub-atmospheric pressure is produced in the condenser, a controlling valve in said suction connection, said valve comprising differential chambers containing respectively piston valves of different cross-section, said chambers being connected respectively to the suction side of the casing and to the condenser 115 120 125 130

side, and restricted, slotted ports connecting said chambers and controlled by said piston valves whereby a given pressure in the suction inlet produces a different pressure in the condenser.

11. A cooling system of the character described comprising a combustion engine having a cooling space and a fuel suction inlet, a condenser, a passage connecting the 10 cooling space with the condenser and discharging into the latter, a return passage from the condenser to the cooling space, a suction connection between the condenser and said fuel suction inlet, an air inlet to 15 the cooling system, and means controlled by relative pressures existing in the suction inlet and the cooling system for controlling said air inlet.

12. A cooling system of the character described comprising a combustion engine having a cooling space and a fuel suction inlet, a condenser, a passage connecting the cooling space with the condenser and discharging into the latter, a return passage 25 from the condenser to the cooling space, a suction connection between the condenser and said fuel suction inlet, pressure-controlled means responsive to pressure in said suction connection to maintain a determined 30 pressure in the cooling system for all degrees of pressure in said fuel suction inlet, an air inlet to the cooling system, and means whereby said air inlet is controlled by said pressure-controlled means.

13. A cooling system of the character described comprising a combustion engine having a cooling space and a fuel suction inlet, a condenser, a passage connecting the cooling space with the condenser and discharging into the latter, a return passage 40 from the condenser to the cooling space, means for admitting vapor from the cooling system into said return passage, a suction connection between the condenser and said fuel suction inlet, and pressure-controlled 45 means responsive to pressure in said suction connection to maintain a determined pressure in the cooling system regardless of variations of pressure in said fuel suction inlet. 50

14. A cooling system of the character described comprising a combustion engine cooling space, a condenser, a passage connecting the cooling space with the condenser and discharging into the latter, a return passage 55 from the condenser to the cooling space, suction-producing means, a suction connection between the condenser and said suction-producing means, and means in said suction connection responsive to differences in pressure existing between said suction means and said condenser for maintaining a substantially constant pressure in the condenser. 60

In testimony whereof we have hereunto subscribed our names.
